UNITED STATES PATENT OFFICE.

WATSON HURLBURT, OF CHICAGO, ILLINOIS.

ELECTRODE FOR ANNEALING AND HEATING SYSTEMS.

1,398,192.

Specification of Letters Patent. Patented Nov. 22, 1921.

Application filed February 24, 1919. Serial No. 273,596.

To all whom it may concern:

Be it known that I, WATSON HURLBURT, a citizen of the United States, residing at Chicago, in the county of Cook and State of Illinois, have invented a new and useful Improvement in Electrodes for Annealing and Heating systems, of which the following is a specification.

My invention relates more nearly to annealing and heating systems, but it may be used wherever an insufficiency of contact results in a poor transmission of the current, caused most likely by irregularity of one or both surfaces over which the current must travel. My method absolutely insures that the current shall have equal access to each and every part of a surface, however irregular, thus I get a uniform and evenly distributed current which of course gives an evenly distributed heat. The method by which I attain this, consists in injecting a layer of a liquid electrolyte between the two surfaces, and confining it at the sides, this fills all the little irregularities of an uneven surface, and upon its conversion into steam, a greater degree of resistance is attained which increases the heating qualities of the current. The idea of a mobile substance like a liquid to get a contact on any kind of a surface where the liquid forms the intermediary in a bulk is of course old and well known, but the manner in which I apply and control it is new and novel, and is a valuable adjunct to the art of annealing and heating, when a roughness of the surface occurs where contact is desired.

I do not wish to be limited to the exact details of construction herewith shown, as various deviations from that illustrated would not depart from the spirit of my invention.

The preferred construction as outlined in my invention is illustrated in the accompanying drawings in which:—

Figure 1 is a general elevation of the mechanism embodying my invention, the portion shown in full lines showing the parts ready for the current to be turned on, that in dotted lines ready for the operation of the press.

Fig. 2 is a section on line 2—2 of Fig. 1.

Fig. 3 is a section on line 3—3 of Fig. 1 showing the insulated bolt securing the electrode to the operating arm.

Fig. 4 is a plan view, parts of the power press being broken away.

Fig. 5 is an enlarged detail section on line 5—5 of Fig. 1 with the irregularities exaggerated.

Fig. 6 is an enlarged view of the electrolyte container, partly broken away, showing its contents.

Fig. 7 is a view of the shape after being operated upon, 4—5 indicates the parts having been annealed.

Similar figures refer to similar parts throughout the work. The general form of the apparatus as shown and illustrated in the drawings where 1 is the table or support for the work, the frame 2, carrying head, 3, plunger, 4, bumper piece, 4^a, and driving wheel, 4^b, these constitute the main parts of the press. The + electrode 5 and — electrode 6 conform to the general outline and fit over the shape to be treated, and have a forward and backward adjustment, by the hand lever 7 pivoted at 8, and pins 9 and 10 engaging in slots 11 and 12 formed on extensions 13 and 14 of the arms 15 and 16. Extensions 17 and 18 of arms 15 and 16, carrying bolts 19, 19^a, 20 and 20^a insulated from electrodes 5 and 6, form the connection between the arms 15 and 16 and electrodes 5 and 6 shown in Fig. 1. A standard 21 having a foot 22 and connected to table 1 by bolts 23 and 24 forms the support for the electrodes and allied parts. The upper part of standard 21 is enlarged and slotted out as shown at 25 Fig. 1, to allow the passage of arm 15 therethrough. An extension 26 with 25 is shown at 27. Similar slots to guide arms 16 are formed as shown at 18^a and 21^a. Bolt 20 shown in detail in Fig. 3, has the insulating washers 20^b and 20^c and 20^d incased by the insulating sleeve 20^a, also bolts 18^b, 18^c, 19, 19^a, and 20^a are insulated in like manner.

To anneal an object as the shape 28, preparatory to bending or offsetting, it is placed upon the block 29 which rests on table 1 of the operating press. Spaced a suitable distance from block 29 under and in alinement with 28 is a similar block 30, in thickness as much less than 29 as the amount of offset required in the piece under treatment. Laid on top of shape 28 is the block 31 of a sufficient height above 28 so that the bumper shall clear the electrode 5 when operated. Spaced from block 31 in alinement with 28 and on top of 28 is the block 32, as much thicker than 31 as the amount of offset re-

quired in the piece under treatment. The electrodes being adjusted and a certain amount of electrolyte allowed to flow into the canal 33 and 33^a by opening valves 34 and 35, and out through the perforations 36 where it fills the spaces 37, 37^a around and about any irregularities there might exist as at 38 exaggerated in Fig. 5. Should the electrodes be prevented from lying close against the surface of the shape by any protuberances, stops 39 are provided to prevent the escape of the electrolyte sidewise consisting of the inner flexible member 40, as asbestos, that will withstand a high heat, and a metallic retaining piece 41 supporting the flexible member by screws 42 passing through both pieces into the electrode. The receptacles 43 for the electrolyte 44 being raised somewhat above the level of the canals 33 and 33^a gives a slight pressure to the fluid causing it to quickly fill the space between the contact surfaces. Valves 34 and 35 are closed after a proper supply has descended, thus when the current heats the parts and steam is generated the added pressure tends to more thoroughly force the liquid and steam into minute pockets or fissures, through the cutting off of the egress at the sides. Through presence of the electrolyte between the surfaces, and full contact established by this means I am enabled to get a very evenly distributed current between the two parts, thus a uniform softening follows, enabling me to get a proper bend throughout the desired area.

When the electrolyte has been allowed to fill the space between the surfaces and the supply valve closed, the current of low voltage and high amperage is switched on, heating is at once set up, when the liquid begins to be transformed into steam, and gathering pressure, a small amount will issue at the junction of the shape 28 and the flexible member 40, but the supply in the canals 33 and 33^a should be plentiful for the time necessary for the part to attain the proper

annealing. At this juncture the current is turned off and at once lever 7 is thrown to the dotted position in Fig. 1 and the operation of the press next deforms the part 28 according to limiting pieces 30 and 32, as shown by dotted lines in Fig. 2.

Claims:—

1. In an electrode the combination of a cavity in said electrode, passages connecting said cavity with the contact surface of said electrode, an electrolyte, a container for said electrolyte and means for controlling the supply of said electrolyte. 55
2. In an electrode the combination of a cavity in said electrode, passages connecting said cavity with the contact surface of said electrode, an electrolyte, a container for said electrolyte, means for controlling the supply of said electrolyte, and means for confining 65 said electrolyte at said contact surface.
3. In an electrode having the contour of a desired shape, a primary passage in the interior contiguous to and following the general outline of said contours, smaller passages forming outlets to the primary passages, an electrolyte, a source of supply for said electrolyte spaced from said electrode, and at a higher level than the primary passage, and means for control consisting 75 of a one way cock.
4. In an electrode the combination of a metal piece to be acted upon, a canal in the surface of contact of the electrodes, a flexible retainer, means for supporting the flexible 80 retainer in contact with said metal piece to be acted upon, a main passage in the electrode connected by smaller passages with the contact surface canal, a liquid electrolyte, a container for the electrolyte connection between the electrolyte container and the main passage, means for controlling the supply of the electrolyte, and means for deforming the piece, as and for the purpose specified. 85

WATSON HURLBURT.
